Des. 213,720
Patented Apr. 1, 1969

213,720

LIGHTING CASING

Edwin F. Osborne, Jr., Houston, Tex., assignor to
Esquire, Inc., New York, N.Y., a corporation of
Delaware

Filed Nov. 8, 1967, Ser. No. 9,331

Term of patent 14 years

Int. Cl. D26—03

U.S. Cl. D48—20

Fig. 1.

Fig. 2.

FIG. 1 is a front perspective view of the lighting casing embodying my new design;

FIG. 2 is a rear perspective view thereof.

The support pole is fragmentarily shown in broken lines in FIGS. 1 and 2 for illustrative purposes only.

I claim:

The ornamental design for a lighting casing, as shown and described.
